UNITED STATES PATENT OFFICE

2,044,881

WEATHER STRIP RETAINER

August William Louis Hartbauer, Chicago, Ill.

Application November 27, 1931, Serial No. 577,554

6 Claims. (Cl. 20—35)

This invention relates to a weatherstrip retainer and particularly to a means for releasably securing weatherstripping to doors and especially refrigerator doors.

In general the conventional method of attaching weatherstripping is by means of nails. The weatherstripping as a rule is made with tabs, or if moulded has depressions for nails which are placed several inches apart. In some instances washer plates which are perforated to receive the nails are used. Any of these types of fastening utilize too great an amount of the space available for weatherstripping, thereby reducing the width of the surface contact of the weatherstripping.

The object of this invention is to utilize practically all of the space available for weatherstripping and to apply a retainer that will not restrict the bearing surface of the weatherstrip in service.

It is a further object of this invention to apply a retainer that will not distort the bearing surface or prevent free compression of the weatherstrip in service.

An additional object of this invention is to apply a retainer suitable for use with any form of resilient weatherstripping materials.

These and other objects and advantages of this invention will be fully set forth in the following description made in connection with the accompanying drawing in which like reference characters refer to the same parts throughout the different views in which:

Figure 1 is a view in elevation of a wood refrigerator door and frame facing the inside of the door and showing the weatherstripping on the four sides of the door;

Figure 2 is a view in end elevation of the door of Figure 1;

Figure 3 is a sectional view on an enlarged scale taken on the line A—A of Figure 1 and showing the weatherstrip and retainer in operative position;

Figure 4 is an isometrical view, partly in section, taken at A—A of Figure 1 showing the weatherstrip as applied, and also showing a corner of the weatherstrip bent upwardly to show application thereof when points of the prongs of the retainer (shown in dotted lines) are embedded in the bearing face of the door after passing through the weatherstrip;

Figure 5 is a cross sectional view of a modified application of the invention, the application being with metal inner and outer door panels;

Figure 6 is a front elevational view of a portion of the retainer of the invention;

Figures 7 and 8 are front elevational views of modified forms of retainers showing variations in contours of the prongs; and

Figure 9 is an isometrical view, partly in section, showing assembly of weatherstrip and retainer and showing one of the prongs riveted or bent over.

In Figure 1 stiles 1 and 2, top rail 3 and bottom rail 4 are joined together at the corners 5 in a suitable way to form the frame of the door structure. To the stiles 1 and 2 and rails 3 and 4 is secured the outer sheet 6 and inner lining 7, the space 8 between the outer sheet 6 and the inner lining 7 being utilized for any desired form of insulation.

As shown in Figure 3 the inner face 9 of the stile 1 is set back from the edge 10 of stile 1 to provide the bearing surface 11 for the weatherstrip 12. Door frame members 13 are recessed at the bearing surface 14 to provide bearing for the weatherstrip 12. The door frame members 13 are also recessed for attachment of lining 15. Sheathing 16 is fastened to the exterior face of the frame 13. The space 17 between lining 15 and sheathing 16 is utilized for any desired form of insulation. The construction just described extends along stiles 1 and 2, top rail 3 and bottom rail 4.

In applying the door to the door frame members hinges are used; opposite the hinges a suitable locking device is applied. In manipulating the door the weatherstrip 12, which may be of any suitable resilient material, is positioned between the bearing surfaces 11 and 14 of the stiles 1 and 2 and rails 3 and 4, also door frame structure 13 and compressed by the action of the door in closing to insure proper contact with these bearing surfaces.

The weatherstripping 12 may be secured to either the door or the door frame members. It has been shown in Figures 1 to 4 inclusive, secured to the door members; that is, stiles 1 and 2 and rails 3 and 4.

The stiles 1 and 2 and rails 3 and 4 are provided with the groove 18 into which the weatherstrip 12, which is in four sections, is positioned. The weatherstrip 12 is secured to the stiles 1 and 2 and rails 3 and 4 with the retainer 19 having prongs 20 which pierce the weatherstrip 12 in alignment with face 9 of stiles 1 and 2 and rails 3 and 4. Prongs 20 are provided with points 22 which may be either driven into the surface 11 or enter a groove provided therein. This secures the prongs 20 and prevents their bending and releasing weatherstrip 12. The portion of the

retainer 19 from which the prongs 20 extend, is secured to the face 9 of the stiles 1 and 2 and rails 3 and 4 with nails or screws 21.

Weatherstrip 12 is restricted against longitudinal movement along the faces 11 of stiles 1 and 2 and rails 3 and 4 by the inserted prongs 20 of the retainer 19. It will be understood, however, that the compression and expansion of that portion of the weather strip 12 extending outwardly from said retainer 19 and its prongs 20 is not restricted transversely because of the upwardly and downwardly sliding contact or the lateral sliding contact, as the case may be, of the weatherstrip 12 on the prongs 20 of the retainer 19. That portion of the weatherstrip 12 which projects from the retainer 19 to the edge 10 of the stiles 1 and 2 and rails 3 and 4, the outer edges of which have been numbered 23, is in yielding contact with surfaces 11 and 14. On account of this yielding contact, the flexible and resilient nature of the weatherstrip material, and the upwardly and downwardly sliding contact, or lateral sliding contact, as the case may be, of the weatherstrip 12 on the prongs 20 of the retainer, the breaking of contact of the weatherstrip from the bearing surfaces 11 and 14 of the door and the door frame, respectively, when the door is opened, is greatly facilitated.

Figure 5 shows a modified metallic or composite metallic and wood construction in which the weatherstrip 12 is secured in position in the groove 18 and in the bearing surface corresponding to the bearing surface 11 of Figures 3 and 4, by prongs 20 which are an integral part of the inner sheet 24 of the door, instead of extending from a separate retainer such as retainer 19. The inner sheet 24 is secured to the door furrings 26 by nails or screws 25.

It will, of course, be understood that various changes may be made in the form, details, arrangement and proportion of parts without departing from the scope of this invention which generally consists of devices capable of carrying out the objects set forth and defined in the appended claims.

I claim:

1. A metallic weatherstrip retainer, said retainer having a body portion, one of the edges of the body portion being divided into alternate individual, separated, elongated spaces and individual, separate, elongated prongs.

2. The combination of a metallic weatherstrip retainer and a weatherstrip, said retainer having a body portion, said body portion having individual, separated, pointed elongated prongs along the edge thereof and individual, separated, elongated spaces between said prongs, said prongs extending through said weatherstrip, said weatherstrip being of flexible and resilient material and adapted to slide upon the prongs of said metallic retainer.

3. A weatherstrip retaining means comprising a supporting member, said supporting member being provided with two surfaces, one transverse to the other, a groove between said surfaces, a weatherstrip, a metallic retainer, said metallic

retainer being provided with elongated prongs, with elongated spaces between said prongs, said metallic retainer being adapted to be held against both surfaces and with the prongs of the retainer piercing the weatherstrip, a portion of said weatherstrip lying in said groove and another portion thereof bearing against one of said surfaces, said weatherstrip being of flexible and resilient material and adapted to slide upon the prongs of said metallic retainer.

4. A weatherstrip retaining means comprising a supporting member, said supporting member being provided with two surfaces, one transverse to the other, a groove between said surfaces, a weatherstrip, a metallic retainer, said metallic retainer being provided with elongated prongs, with elongated spaces between said prongs, said metallic retainer being adapted to be held against both surfaces and with the prongs of the retainer piercing the weatherstrip, a portion of said weatherstrip lying in said groove and another portion thereof adapted to bear against one of said surfaces, said weatherstrip being held by said metallic retainer against longitudinal movement but said last mentioned portion of said weatherstrip not being held against transverse or lateral extension from said retainer when compressed, said weatherstrip having sliding engagement on the prongs of said retainer.

5. A weatherstrip retaining means comprising a main body portion, said body portion being L-shaped and acting as a support, a weatherstrip, a metallic weatherstrip retainer, said metallic weatherstrip retainer having a body portion, sharpened elongated prongs extending from said body portion, elongated spaces between said prongs, the body portion of said retainer being secured against one surface of said L-shaped support and the ends of prongs after piercing the weatherstrip entering the other surface of said support to aid in supporting the weatherstrip, said prongs permitting said weatherstrip to slide thereon in two directions.

6. A weatherstrip retaining means comprising a supporting member, said supporting member being provided with two surfaces, one transverse to the other, a groove between said surfaces, a weatherstrip, a metallic retainer, said metallic retainer being provided with elongated prongs, with elongated spaces between said prongs, said metallic retainer being adapted to be held against both surfaces and with the prongs of the retainer piercing the weatherstrip, a portion of said weatherstrip lying in said groove and another portion thereof adapted to bear against one of said surfaces, said weatherstrip being held by said metallic retainer against longitudinal movement but said last mentioned portion of said weatherstrip not being held against transverse or lateral extension from said retainer when compressed, said weatherstrip having sliding engagement on the prongs of said retainer but not to cover the upper spaces between said prongs above said weatherstrip.

AUGUST WILLIAM LOUIS HARTBAUER.
